UNITED STATES PATENT OFFICE

146,592

DESIGN FOR A COMBINED HOLDER FOR
DECANTER AND GLASSES

Pauline Blume, New York, N. Y.

Application February 9, 1946, Serial No. 126,406

Term of patent 3½ years

(Cl. D44—7)

To all whom it may concern:

Be it known that I, Pauline Blume, a citizen of the United States, residing in New York city, in the county of New York and the State of New York, have invented a new, original, and ornamental Design for a Combined Holder for Decanter and Glasses, of which the following is a specification, reference being had to the accompanying drawing, forming a part thereof, in which—

I claim:

The ornamental design for a combined holder for decanter and glasses, as shown and described.

PAULINE BLUME.
